MECHANISM FOR USE IN APPLYING PRESSURE TO SHOE BOTTOMS

Francis J. Better, Beverly, Mass., assignor to
 United Shoe Machinery Corporation, Flemington, N. J., a corporation of New Jersey

Application November 22, 1940, Serial No. 366,736

33 Claims. (Cl. 12—33)

This invention relates to machines for use in applying pressure to shoe bottoms and is illustrated herein with reference to improved means in such machines for relatively positioning shoes and shoe bottom members before pressure is applied thereto. This application is a continuation in part of my copending application Serial No. 315,784 filed January 26, 1940, and directed to mechanism for use in applying pressure to shoe bottoms.

During recent years there has been a great increase in the manufacture of shoes, particularly of the sandal type, having their bottom portions made up of several different members which are cemented together to produce what are known in the trade as clog, wedge heel and platform shoes. These shoes have a conventional type of insole to which the upper may be lasted in any usual manner but their bottom portions have midsole members or wedge heels, or sometimes both, interposed between the shoe bottoms and their outsoles. In the case of a wedge heel shoe, the wedge heel is usually shaped to fill in the entire arch at the shank and heel portion of the shoe bottom so that the outsole lies substantially flat over its entire area.

When shoes of these types are to have their bottom members, including the outsole and the midsole or wedge heel, attached by cement alone in a single cement attaching operation, it is difficult to position the shoe and its bottom members relatively to each other in a cement sole attaching machine or press and to maintain the parts in their proper relative positions until the cement attaching operation has been completed.

An object of the present invention is to provide improved means in a machine of the type referred to for relatively positioning a shoe and a plurality of shoe bottom members and maintaining them in proper relative positions until they have been attached together by cement.

To this end and in accordance with an important feature of the invention, there is provided an improved pad box structure having a sole receiving pad and means on the pad box for locating the sole on the pad, together with additional means for positioning on the sole a shoe part or bottom member adapted to be interposed between the shoe bottom and outsole in the finished shoe. Moreover, the pad box may be further provided with means arranged to position the shoe relatively to the shoe bottom member and sole.

As herein illustrated, the sole positioning

means includes a gage for locating an end portion of the sole in a predetermined position on the pad and this gage is arranged to remain fixed lengthwise and widthwise of the pad during the operation on the shoe. The means for positioning the intermediate shoe bottom member on the sole comprises a gage for engaging an end portion of the member and additional gages for engaging the opposite side portions 5 of said member. As therein illustrated, these gages are adjustable relatively to each other and to the sole gage to permit them to operate on shoes of different sizes. The shoe positioning means likewise comprises gages for engaging the 10 opposite sides of an end portion of the shoe and positioning it relatively to the corresponding end portions of the shoe bottom member and sole. As illustrated, the gages for engaging the opposite sides of the intermediate bottom member 15 are arranged for equal and opposite swinging movement toward and away from the shank portion of the sole and said bottom member and, in order to limit or control this movement in accordance with the shapes of the members being 20 operated upon, an adjustment is provided whereby these gages can be made to engage the opposite edge faces of the sole substantially simultaneously irrespective of its shape. Moreover, the gage for positioning the end portion of the 25 shoe bottom member as, for example, the rear or heel end thereof, can be adjusted lengthwise and laterally relatively to the sole gage and the intermediate or shank gages and, in accordance with another feature of the invention, the shoe 30 gages, which are likewise movable equally and oppositely toward and away from the shoe, can be adjusted bodily widthwise of the pad and relatively to the sole gage and the gages for positioning the intermediate shoe bottom member. 35 The arrangement of the entire heel gage mechanism is such, moreover, that it can be adjusted lengthwise of the pad as a unit and it is mounted yieldingly on the pad box to permit it to move downwardly as a unit with the shoe, sole and intermediate bottom member to prevent scarring these parts during the cement attaching operation.

In the manufacture of shoes of the types referred to, particularly wedge heel shoes, the intermediate shoe bottom member or wedge heel may sometimes be attached to the bottom of the shoe by cement or driven fastenings before the outsole is attached to the shoe bottom. In accordance with another feature of the present invention, there is provided, as an alternate form

or modification of the invention, improved means for locating a sole on the pad of the pad box, means for positioning on the sole a shoe bottom member, such as a wedge heel which has been attached to a shoe bottom, and additional means for effecting relative adjustment between the two positioning means heightwise of the pad. As herein illustrated, the sole locating means comprises a forked gage adapted to engage the heel portion of the sole and locate it in a predetermined position on the pad. The means for positioning the shoe bottom member or wedge heel relatively to the sole comprises another gage arranged to engage the rear surface or wall of the wedge heel. The wedge heel gage, as illustrated, is mounted for swinging movement about a pivot or axis extending widthwise of the pad and this gage may be adjusted about its pivot to vary its heightwise position relatively to the sole locating gage and the pad. Both gages are preferably mounted on a support or carrier member and, as illustrated herein, the carrier member is adjustable lengthwise of the pad so that the positions of the gages may be varied for different shoes. Moreover, in the modified construction the sole locating gage may be adjustable lengthwise in the carrier member, thereby permitting lengthwise adjustment of the gages relatively to each other as well as to the pad. The wedge heel gage is maintained in its adjusted position about its pivot by a spring which permits the gage to yield under pressure but returns it to its adjusted position when the pressure is relieved. Since the shoe and wedge heel have been attached together before the outsole has been attached to the shoe bottom, no positioning means will be required in the present construction for positioning the shoe, thereby simplifying the construction and making it cheaper to build.

With the above and other objects and features in view the invention will now be described in detail in connection with the accompanying drawings and will thereafter be pointed out in the claims.

In the drawings:

Fig. 1 is a side elevation of the pad box embodying my invention with the work mounted therein, the positioning mechanism at the heel end of the pad box being shown in section;

Fig. 2 is an enlarged detail view, partly in section, of one of the positioning mechanisms located at the shank portion of the sole;

Fig. 3 is a plan view of the pad box;

Fig. 4 is a perspective view of the pad structure at the forepart of the pad box;

Fig. 5 is a plan view of the heel portion of the pad box with the top page mechanism removed to show the lower mechanism in full;

Fig. 6 is an enlarged perspective view, partly in section, of the forward portion of mechanism which carries the wedge heel gage;

Fig. 7 is a fragmentary perspective view of a part of the mechanism shown in Fig. 6 but as viewed from the opposite direction;

Fig. 8 is a side elevation of the rear end of the pad box with a modified form of gage mechanism mounted thereon and showing the relative position of the parts of this mechanism when locating a sole and a wedge heel shoe on the pad;

Fig. 9 is a plan view of the construction shown in Fig. 8; and

Fig. 10 is a sectional view taken on the line X-X of Fig. 8.

The invention is illustrated herein as embodied in a cement sole attaching machine of the type illustrated in Letters Patent of the United States No. 2,047,185, granted July 14, 1936, on an application filed in the name of Milton H. Ballard et al., the pad box of that machine, however, being modified by omitting the positioning gages usually employed at the ball line of the sole and shoe and being further modified by providing, at the rear portion of the pad box, heel gage supporting and operating mechanism generally similar to that disclosed in United States Letters Patent No. 2,005,755, granted June 25, 1935, on an application filed in my name. However, the gage mechanism of the present invention involves important changes and improvements over that in the patent last referred to which will be herein-after pointed out in detail.

As disclosed in the Ballard et al. patent, the pad box comprises a box-like structure 10 having mounted therein a flexible fluid filled pad (not shown) adapted to apply pressure to the bottoms of soles and shoes when they are pressed forcibly against the pad by pressure applying abutments 12 and 14 (Fig. 1) carried by the cement sole attaching machine. In the present case the fluid filled pad has mounted on its top side an upper or auxiliary resilient pad 16 of solid rubber preferably covered by a thin layer 18 of leather or similar material to protect the surface of the pad, the forward end of the pad 16, as shown in Fig. 4, having a recess 20 formed around its marginal portion to receive a forepart mask plate 22 without producing a shoulder or ridge on the sole receiving surface of the pad.

The pad box 10 is provided at its forward end with gage arms or fingers 24 which, as disclosed in the Ballard et al. patent, cross each other and are normally urged inwardly under yielding pressure to permit sole gages 26 carried thereby to "find" the opposite edge faces of a sole S placed on the pad by the operator after which the gage arms 24 become locked automatically against movement away from the sole. The sole gages 26 are elongated as shown in Fig. 3 to extend considerable distances toward the toe end of the pad at angles substantially normal to the direction of movement of the gages toward and away from the edge of the sole. This construction permits the gages 26 to operate on soles of different sizes by engaging them rearwardly of the toe end so that a second set of forepart gages usually employed on the pad box for engaging the sole at the ball line may be dispensed with.

Mounted on each gage arm 24 above the sole gage 26 is a shoe gage 28 arranged to engage the opposite sides of a shoe A at the toe end when the shoe is mounted on the sole and each shoe gage 28 is arranged to be adjusted relatively to its sole gage, to determine the proper overhang of the sole edge relatively to the shoe, by eccentric adjusting mechanism 30 which is fully disclosed in the Ballard et al. patent. These forepart sole and shoe gages are operated by depression of a treadle (not shown) on the cement sole attaching machine which swings a bell crank lever 32 (Fig. 3), pivoted on a horizontal shaft 34, in a clockwise direction as viewed from the front, and which, through further mechanism (not shown) connected to the bell crank lever by a link 36, causes the forepart gages to operate, this same bell crank lever 32 also operating, by means of another link 38 and a bell crank lever 40, to permit a transverse slide 42 located at the heel portion of the pad box to be actuated as disclosed in

my prior patent by being moved rearwardly by a compression spring 44 (Figs. 1 and 5) to cause a pair of equally and oppositely movable gage arms or fingers disclosed in that patent to be moved inwardly into engagement with the heel end of the sole.

As indicated above, the heel gage mechanism of the present invention, although embodying features disclosed in my prior patent, also comprises certain important structural changes and improvements which permit this mechanism to position a sole, a wedge heel and a shoe relatively to each other on the pad 16 prior to attaching these parts together by cement. As shown in my prior patent, the rear or right-hand end of the pad box, as viewed in Fig. 1, is provided with vertical guideways in which is mounted a slide 46 having formed at its upper end a rearwardly extending portion 48 which, in the present machine, is inclined at about the same angle as the upper surface of the pad 16, the slide 46 being maintained yieldingly in its uppermost position in the guideway by a pair of compression springs 50. The portion 48 of the slide has mounted thereon for sliding movement lengthwise of the pad a support or carrier member 52 which may be adjusted lengthwise along the portion 48 and secured in adjusted position by a thumb screw 54 extending through a slot 56 in the portion 48.

The slide 46 also has secured to its upper end by screws 58 (Fig. 1) a forwardly extending bracket 60, the upper surface of which forms a support for a rear portion 62 of the pad 16, this portion 62 being reduced in width and arranged to extend rearwardly some distance beyond the heel end of the largest shoe that would ever be operated upon by the pad. The upper surface of the rear portion 62 of the pad lies in the same plane as the rest of the pad and forms a continuation of its upper surface and the protective cover 18 overlies this entire surface, as shown in Fig. 1.

Secured by screws 64 to the forward side of the support or carrier member 52 is a sole gage 66 consisting of an L-shaped member having a forwardly extending plate-like portion arranged to overlie the heel end of the pad. As best shown in Fig. 5, the sole gage 66 is forked at its forward end so that it will readily engage the heel portion of the sole S at opposite sides of its longitudinal median line, irrespective of the size of the sole. It will also be noted that the sole gage 66 is fixed with respect to the pad when engaging a sole although, of course, it can yield downwardly with the carrier member 52 and vertical slide 46 as the heel portion of the pad is pressed downwardly against its support 60 under pressure from the sole and shoe. Moreover, the sole gage 66 may be initially adjusted lengthwise of the pad along with the carrier member 52 for the size of sole being operated upon and then secured in adjusted position by means of the thumb screw 54.

As best shown in Fig. 1, the upper portion of the carrier member 52 is provided with a transverse T-slot in which is mounted the slide 42 above referred to. Above the slide 42 the carrier is cut away to receive a pair of gage fingers 68, 70 similar in construction to the sole engaging fingers of my prior patent and being interconnected by gear segments 71 for equal and opposite swinging movement about pivot pins 73, 75 extending upwardly from the fingers into the member 52. As disclosed in my prior patent, the gage fingers 68, 70 are actuated to swing them inwardly toward the sole and shoe on the

pad by rearward movement of the transverse slide 42 under the action of the compression spring 44 referred to, this movement being permitted by counterclockwise movement of the bell crank lever 40 when the treadle of the machine is depressed to move the upper arm of the lever 32 toward the right, as viewed in Fig. 3. The slide 42 is provided with an inclined cam slot 72 (Fig. 5) and the gage finger 70 carries a roll 74 which projects into this slot so that movement of the slide rearwardly closes the gage fingers 68 and 70 yieldingly into engagement with the work, as shown in Figs. 3 and 5. Reverse movement of the bell crank lever 40 causes a roll thereon to engage the slide 42 and press it forwardly against the spring 44, thereby retracting the gage fingers 68 and 70 away from the sole and shoe. As described in my prior patent, the angle of inclination of the cam slot 72 is such that the gage fingers become locked against movement away from the work after they have engaged and positioned it on the pad.

The gage fingers 68 and 70 have pivotally secured respectively to their left-hand ends, as viewed in Figs. 3 and 5, extension arms 76, 78 which extend forwardly over the pad and terminate substantially opposite the shank portion of the sole on the pad, preferably about midway between the heel breast line and the ball line of the sole. These arms or extensions 76, 78 carry respectively on their forward ends sole gages 80, 82 and wedge heel gages 84, 86 (Figs. 1 to 3, inclusive). As best shown in Fig. 2, these gages for engaging the shank portion of the sole S and a wedge heel W are relatively adjustable on the ends of the extension arms by eccentric adjusting mechanisms 88 of the same construction as the adjusting mechanisms 30 on the fore-part gages, these adjusting mechanisms being fully described in the Ballard et al. patent and serving to determine the overhang or extension of the sole relatively to the wedge heel, as clearly shown in Fig. 2.

Since the gage fingers 68, 70 and their extension arms 76, 78 are moved together equal amounts in opposite directions toward and from the sole by the intermeshing gear segments 71, it is necessary that an adjustment be provided whereby the sole gages on the fingers may be caused to engage the opposite sides of the shank portion of the sole substantially simultaneously because the sole should not be moved any appreciable amount laterally of the position in which it is placed on the pad. Accordingly, the extension 76 of the finger 68 has been made in two sections pivoted to each other by a pin 90 (Fig. 3) and spring pressed away from each other forwardly of the pin 90 by a compression spring 92 seated in recesses in the two sections. The forward section of the arm 76 has a rearwardly extending tail 93 through which is threaded a stop screw 94 arranged to engage an adjacent portion of the rear section 76 and thereby determine the positions of the two sections relatively to each other and also to determine the position of the sole and wedge heel gages carried thereby relatively to the opposite sole and wedge heel gage laterally of the pad. It will be seen therefore that, through the adjustment just described, the sole and wedge heel gages at the shank portion of the sole may be initially adjusted laterally for soles of different shapes so that the equal and opposite swinging movement of the gage fingers under the action of the transverse slide 42 will cause the gages to con-

tact with the work at substantially the same time and without moving the sole any appreciable amount laterally of the pad. In operation, these shank gages engage the opposite edge faces of the sole and become locked, as explained above, so that the wedge heel gages 84, 86 will be located properly to position the forward portion of the wedge heel W relatively to the shank portion of the sole. Before these shank gages are operated, however, by depression of the treadle, the wedge heel is positioned lengthwise of the pad by a wedge heel gage 96 adapted to engage the wedge heel W at its rear end, as shown in Figs. 1 and 3.

Referring to Fig. 1, the carrier member 52 is provided above the gage finger 70 with a T-slot 98 (Figs. 3 and 5) extending lengthwise of the pad and in which is mounted a longitudinal slide 100. The slide 100 is adjustable lengthwise of the pad by an adjusting screw 102 threaded into the rear end of a substantially horizontal casting 104 which, together with an upper casting 106, is secured by bolts 108 to the upper surface of the member 52. The adjusting screw 102 has a circular flange 110 formed thereon which engages a correspondingly shaped slot 112 in the rear portion of the slide 100 so that when the screw 102 is turned the slide 100 will be moved lengthwise of the pad box.

The forward end of the slide 100 is enlarged, as best shown in Figs. 1 and 6, and has formed therein a T-slot 114 which extends widthwise across the front of the slide and the bottom surface of which is inclined at an angle of about 80° to the horizontal. Mounted in this T-slot 114 for movement widthwise of the pad is an intermediate slide 116 which extends some distance above the forward end of the slide 100 and is provided in its forward side with a T-slot 118 which extends heightwise of the intermediate member and is located substantially centrally thereof, this T-slot 118 being likewise inclined at an angle of about 80° to the horizontal. Mounted for heightwise movement in the T-slot 118 is a carrier member 120 to the lower end of which is secured by screws 122 the wedge heel gage 96 above referred to and which, as best shown in Fig. 3, is forked similarly to the sole gage 66 and is preferably covered on its work engaging surface with a thin layer 124 of leather, rubber or similar material, to prevent the gage from scarring the wedge heel. It will be seen from Figs. 1 and 3 that the operative surface of the wedge heel gage 96 is inclined rearwardly at a slight angle to the vertical in the same manner as its supporting members and this angle is approximately the same as the angle of the rear edge face of the wedge heel when it is positioned on the pad.

The wedge heel gage 96 is adjustable laterally of the pad by movement of the intermediate slide 116 in the transverse slot 114. This adjustment is accomplished by a screw 126 threaded into a hole formed in the forward end of the slide 100, rearwardly of the T-slot 114, the outer portion of this hole being counterbored, as shown at 128 in Fig. 6, so that it breaks into the T-slot 129 between the T-slot and counterbore 128. The adjusting screw 126 is provided with a knurled head 130 and, at the portion thereof located in the counterbore, it has a flange 132 which fits the counterbore and the perimeter of which projects through the opening 129 and engages a slot 134 (Fig. 7) extending heightwise of the rear portion of the intermediate slide 116. Ac-

cordingly, adjustment of the screw 126 in or out of the slide 100 effects an adjustment of the intermediate slide 116 laterally of the slide 100 and of the pad. The counterbore 128 is of sufficient depth to provide for any lateral adjustment that will be required of the wedge heel gage 96 relatively to the sole gage 66 which, as stated, is fixed with respect to the pad.

It is desirable to have the wedge heel gage 96 supported yieldingly so that it can move downwardly with the wedge heel during any initial compression of the rubber pad 16, 62 that may take place before the pressure on the shoe has become great enough to move the entire heel gage mechanism downwardly with the vertical slide 46 against the compression springs 50. This yielding arrangement of the wedge heel gage 96 is effected by mounting a compression spring 136 (Fig. 1) in a hole extending heightwise of a lower portion of the intermediate slide 116, the upper end of the spring engaging the gage supporting member 120 thereby supporting this member and the gage 96 in its T-slot 118 so that the gage is normally maintained in its uppermost or operative position but can yield downwardly under relatively light pressure to permit the gage to travel downwardly with the wedge heel during any initial compression of the pad and before the entire gage mechanism moves downwardly as a unit with the slide 46 under the full sole attaching pressure.

In addition to the sole gage 66, the shank gages 80, 84 and 82, 86, and the wedge heel gage 96, the last two of which are adjustable relatively to the sole gage 66, the pad box is further provided with a pair of shoe gages 138, 140 arranged to engage the opposite sides of the shoe A which is to be mounted on the sole S and wedge heel W and cement attached thereto simultaneously with the cement attachment of the wedge heel to the rear portion of the sole. It will be recalled that the position of the forepart or toe end of the shoe will already have been determined by the forepart shoe gages 28 so that, when the shoe is placed on the sole and wedge heel, its forepart will be properly located with respect to the sole. The shoe gages 138, 140 at the heel end of the shoe are of substantially the same construction as the shoe gages disclosed in my prior patent except that, in the present case, the shoe engaging ends of the gages extend upwardly a substantial distance to insure that they will always engage the shoe irrespective of varying heights of wedge heels. The mechanism for actuating these shoe gages is of substantially the same construction as is disclosed in my prior patent and, accordingly, only a brief description of these mechanisms will be necessary here.

The substantially horizontal casting 104 carries at its forward end a transverse slide 142 to which the shoe gages are pivoted and which is normally secured to the casting 104 by a friction clamp including an adjusting lever 144 (Figs. 3 and 5) which provides means for adjusting the shoe gages bodily with respect to the shank gage fingers 68 and 70 to position the shoe gages in a desired lateral position relatively to the shank gages, the wedge heel gages and the sole gage 66. The shoe gages 138, 140 are pivoted on pins 146, 148 carried by the slide 142 and, as shown in Fig. 3, the rear portions of the shoe gages are interconnected for equal and opposite movement about their pivots by intermeshing gear segments 150. The shoe gage 140 carries an upwardly projecting roll 152 which is located in an in-

clined cam slot 154 formed in an upper transverse slide 156 arranged for forward and rearward movement in the upper casting 106. This movement of the upper slide is effected by a link 158 secured at its forward end by a ball and socket joint to an upstanding bracket 160 fastened to the slide 156. As disclosed in my prior patent, the inner end of the link 158 is pivotally connected to an arm (not shown) pivotally connected to a forwardly and rearwardly swinging frame member of the cement sole attaching machine which carries the pressure applying abutments 12 and 14 and, when this swinging frame is swung forward manually to bring the abutments into pressure applying position, the link 158 moves the upper slide 156 forwardly into the position shown in Fig. 3, to close the shoe gages 138, 140 with equal movements against the opposite sides of the shoe A, thereby positioning the heel end of the shoe relatively to the wedge heel W and sole S. Later in the cycle of the cement sole attaching machine, the swinging frame member is returned automatically to its rearward position which, of course, moves the slide 156 rearwardly to open or retract the shoe gages from their operative engagement with the shoe. It should be pointed out that the angle of inclination of the cam slot 154 in the slide 156 is such that, when the shoe gages have been brought into engagement with the shoe and have moved it into a proper position relatively to the wedge heel and sole, the shoe gages will be locked against movement away from the shoe until the slide 156 is moved rearwardly by the swinging frame.

As indicated above, the adjusting lever 144 provides a transverse adjustment for the shoe gages bodily with respect to the wedge heel gages and the sole gage and, as fully disclosed in my prior patent, this adjusting mechanism comprises an eccentric pin 162 on the lever 144 which engages a T-slot (not shown) in the slide 142 and moves the slide laterally with respect to the casting 104, thereby moving the pivots 146, 148 and the shoe gages 138, 140 bodily in a transverse direction relatively to the rest of the heel gage mechanism.

In the use of the pad box the operator first adjusts the entire heel gage mechanism as a unit lengthwise of the pad until the sole gage 66 is located in the desired position for the length of the sole being operated upon, this adjustment being retained by the thumb screw 54. He then makes the desired lateral and longitudinal adjustments of the wedge heel gage 96 by means of the thumb screws 126 and 102. If it is necessary, he also adjusts the shank gages 80, 84 laterally relatively to the opposite shank gages 82, 86 by the screw 94 (Fig. 3) and, finally, if it is required for the shape of the shoe being operated upon, he adjusts the shoe gages 138 and 140 bodily transversely of the pad by the adjusting lever 144.

The operator places the sole S on the pad cover 18 with the heel end of the sole engaged and positioned by the forked end of the fixed sole gage 66. It should be understood that the attaching surface of the sole will have been previously coated with cement in the usual manner and, if the cement requires activation to render it adhesive, this will also have been done just prior to placing the sole on the pad. The operator then depresses the treadle of the cement sole attaching machine which causes the sole and shoe gages 26, 28 at the forepart of the

pad box to move inwardly with a yielding action to find the forepart of the sole where it has been placed by the operator on the pad. After the sole gages 26 have both contacted with the opposite edge faces of the sole at the toe end thereof, the gage arms 24 become locked against movement away from the sole, thereby locating the shoe gages 28 in a proper position to receive the toe end of the shoe A and position it properly with respect to the sole.

When the operator depressed the treadle to move the forepart gages into engagement with the sole, the mechanism for operating the shank gage fingers 68, 70 was likewise actuated through the link 38 and lever 40 referred to to permit the lower slide 42 to be moved rearwardly by its spring 44 and swing the shank gages 80, 84 and 82, 86 inwardly with equal and opposite movement into engagement with the shank portion of the sole where, through the inclined cam slot 72 referred to, these gages also become locked against movement away from the sole. Consequently, the gages 84, 86 for engaging the wedge heel adjacent to the shank portion of the sole, are now located in position to receive the wedge heel.

The operator next places the wedge heel W, which may, if desired, be coated with cement on its top and bottom surfaces, upon the rear portion of the sole S in the position determined by the wedge heel gage 96 and the shank gages 84, 86, the gage 96, as stated, having already been adjusted relatively to the sole gage 66 so that the rear portion of the wedge heel will be properly located laterally and lengthwise to provide the desired overhang of the rear portion of the sole with respect to the wedge heel. The operator now places the shoe A on the sole and wedge heel, the shoe having been properly treated on its bottom surface with cement. The forepart of the shoe becomes properly positioned at once by its engagement with the shoe gages 28. Since the heel portion of the shoe A has not yet been positioned relatively to the wedge heel and sole, the shoe gages 138, 140 are now operated to effect this result which is accomplished by the operator when he moves the swinging frame member of the machine forwardly to move the pressure applying abutments 12 and 14 into operative position over the shoe.

It will be seen from the foregoing description, that the present invention provides means for locating the foreparts of a sole and shoe properly with respect to each other on a sole receiving pad, prior to the application of sole attaching pressure, and it further provides in combination with such means, improved means at the heel end of the pad box for relatively positioning the heel portions of the sole and shoe and a wedge heel that is to be interposed between the shoe bottom and the outsole in the finished shoe. The construction is such that the wedge heel will be positioned properly longitudinally of the pad relatively to the shoe and sole by the rear wedge heel gage 96, and the forward portion of the wedge heel will be positioned accurately with respect to the shank portion of the sole by the wedge heel gages 84 and 86 whose positions have been previously determined by the sole gages 80, 82 at the shank portion of the sole.

The modified form of the invention is illustrated in Figs. 8 to 10, inclusive, this construction being of particular utility when a shoe bottom member such as a wedge heel has been at-

tached to the bottom of the shoe separately from the outsole and prior to the sole attaching operation. As shown in Fig. 8, the rearwardly extending portion 48 of the slide 46 has mounted on its upper side a base 164 for the gage mechanism, the base having a grooved under surface which forms a sliding fit with the rear portion 48 of the slide. When the base 164 is located in a desired position on the portion 48, it may be clamped in position by a thumb screw 166, which is threaded into the base 164 and extends through a longitudinal slot 168 in the member 48. A carrier member 170 is connected to the base 164 by a tongue and groove connection and this carrier member is adjusted relatively to the base in a direction lengthwise of the pad by a fixed screw 172. The screw is restrained against lengthwise movement on the base by relatively large cylindrical portions 174, 176 on the screw which engage, respectively, the opposite end portions 178, 180 of the base. The screw 172 is threaded into the carrier member 170 and when it is rotated causes the carrier member to move back and forth, depending upon the direction of rotation.

Slidably mounted in a T slot 182 (Fig. 10) extending in a lengthwise direction through the lower portion of the carrier member 170 is a sole gage plate 184. The plate 184 may be adjusted back and forth in the slot by a thumb screw 186 which is threaded into the carrier 170 and is connected with the plate by a collar 188, which fits into a slot 190 (Fig. 8) formed in one of a pair of legs 192 that form the rear portion of the plate 184. Thus, when the screw 186 is threaded into or out of the carrier 170, the collar 188 causes the gage plate 184 to move backward or forward with the screw. A forked sole gage 194 is pivoted to the plate 184 by a pair of pins 196 so that the gage can move downwardly with the sole when pressure is applied to a shoe on the pad.

Located above the sole gage 194 is a forked wedge heel gage 198 connected to the forward end of a lever 200 for adjustment widthwise of the pad by a transverse slot and tongue arrangement (Fig. 8) and held in position on the lever by a screw 202 which passes through a transverse slot in the lever 200 and is threaded into the gage. The lever 200 is pivoted intermediate of its ends on a pin 204 mounted in a pair of spaced ears 206 formed on the upper part of the carrier 170. The forward end of the lever 200 is normally held in a raised position by a spring 208, which is connected at its upper end to a pin 210 that projects laterally from an extension 212 on the rearwardly extending arm of the lever 200, and at its lower end to a pin 214 (Fig. 8) extending from the lower portion of the carrier member 170. The position in which the lever 200 is normally held by the spring 208 is regulated by an abutment screw 216, which is threaded through the extension 212 and engages an underlying shoulder 218 on the carrier 170.

To operate this gage mechanism on the pad box, the base 164 is first located in a proper position on the portion 48 of the slide 46 and is clamped in position by the thumb screw 166. The adjusting screw 172 is next rotated to move the carrier member 170 until the wedge heel gage 198 reaches a desired position lengthwise of the pad, after which the screw 216 may be adjusted to move the gage 198 into a desired position heightwise of the pad. The sole gage

194 is next adjusted lengthwise into a position where it will locate a sole S' in a desired relation to a wedge heel W' previously attached to a shoe A'. As the slope of the rear face of the wedge heel W' differs with shoe styles, the sole gage 194 may have to be adjusted from time to time with respect to the wedge heel gage 198, depending upon variations in the styles of the shoes operated upon. The pressure may now be applied to cement attach the outsole S' to the shoe and wedge heel W'. The wedge heel W' illustrated in Fig. 8 is an extremely high wedge heel and it will be noted that the gage 198 has been elevated considerably to engage the wedge heel in the proper position. When the pressure is applied, however, and the shoe and heel move downwardly into the pad, the gage 198 can move downwardly with the heel because of the yielding arrangement of the gage lever 200.

Having thus described my invention, what I claim as new and desire to secure by Letters Patent of the United States is:

1. A pad box for use in applying pressure to shoe bottoms having, in combination, a sole receiving pad, means for locating an end portion of the sole on the pad, means for positioning on said end of the sole a shoe part adapted to be interposed between the shoe and sole in the finished shoe, and additional means arranged to position the corresponding end of the shoe relatively to said shoe part and sole.
2. A pad box for use in applying pressure to shoe bottoms having, in combination, a sole receiving pad, means for locating an end portion of the sole on the pad, means for positioning on said end of the sole a shoe bottom member adapted to be interposed between the shoe bottom and sole in the finished shoe, and means additional to said locating and positioning means arranged to position the corresponding end portion of the shoe with respect to said shoe bottom member and said end portion of the sole.
3. A pad box for use in applying pressure to shoe bottoms having, in combination, a sole receiving pad, a gage for locating an end portion of a sole in a predetermined position on the pad, means for positioning on said end portion of the sole a shoe bottom member adapted to be interposed between the sole and a shoe, and means separate from said last-named means arranged to position the corresponding end portion of the shoe relatively to the corresponding end portions of said shoe bottom member and sole.
4. A pad box for use in applying pressure to shoe bottoms having, in combination, a sole receiving pad, a gage for locating the heel portion of a sole on the pad, means for positioning a wedge heel relatively to the heel portion of said sole, and means additional to said positioning means arranged to position the heel portion of a shoe relatively to said wedge heel and the heel portion of the sole.
5. A pad box for use in applying pressure to shoe bottoms having, in combination, a pad for receiving a sole and shoe, means for locating an end portion of the sole on the pad, means for positioning on the sole the corresponding end portion of an intermediate member adapted to be interposed between the shoe bottom and sole in the finished shoe, means arranged to position the corresponding end portion of the shoe relatively to the intermediate member and sole, and means for adjusting said locating and positioning means relatively to one another.

6. A pad box for use in applying pressure to shoe bottoms having, in combination, a pad for receiving a sole and shoe, a gage for locating the heel portion of the sole in a predetermined position on the pad, means for determining the position of a wedge heel on the sole, means arranged to position the heel portion of the shoe relatively to the wedge heel and sole, and means on the pad box for adjusting said gage and said positioning means relatively to one another for shoes of different shapes.

7. A pad box for use in applying pressure to shoe bottoms having, in combination, a pad for receiving a sole and shoe, a gage for locating an end portion of the sole in a predetermined position on the pad, another gage for positioning on the sole the corresponding end portion of a shoe bottom member adapted to be interposed between the shoe and sole in the finished shoe, a pair of gages for engaging an intermediate portion of the sole, means carried by said gages for engaging portions of said shoe bottom member adjacent to said sole gages and positioning said member laterally relatively to the sole, and means for engaging opposite sides of an end portion of the shoe and positioning it laterally relatively to the shoe bottom member and sole.

8. A pad box for use in applying pressure to shoe bottoms having, in combination, a pad for receiving a sole and shoe, a gage for positioning the heel end of the sole in a predetermined position on the pad, said gage being fixed against movement lengthwise and widthwise of the pad during the positioning operation, another gage arranged to engage the rear end of a wedge heel placed on the sole and position it lengthwise relatively to the sole, and means for effecting relative adjusting movement between the two gages.

9. A pad box for use in applying pressure to shoe bottoms having, in combination, a pad for receiving a sole and shoe, a gage for engaging the heel end of the sole and locating it in a predetermined position on the pad, said gage being fixed against movement lengthwise and widthwise of the pad, another gage arranged to engage the rear end of a wedge heel and position it lengthwise relatively to the sole, and means for adjusting the wedge heel gage relatively to the sole gage.

10. A pad box for use in applying pressure to shoe bottoms having, in combination, a pad for receiving a sole and shoe, a gage for locating an end portion of the sole in a predetermined position on the pad, said gage being fixed against movement lengthwise and widthwise of the pad when in operative position, another gage arranged to engage the corresponding end portion of an intermediate shoe bottom member and position it lengthwise of the sole, a pair of equally and oppositely movable gages for engaging the shank portion of the sole, means carried by said gages for positioning adjacent portions of the shoe bottom member relatively to the sole, and means for adjusting said equally and oppositely movable gages laterally of the pad for soles of different shapes.

11. A pad box for use in applying pressure to shoe bottoms having, in combination, a pad for receiving a sole and shoe, a gage for locating the heel end of the sole on the pad, another gage arranged to position the rear end of a wedge heel relatively to the sole, means for positioning the shank portions of the sole and wedge heel relatively to each other, a pair of equally and oppositely movable gages arranged to position the

5 heel end of the shoe relatively to the wedge heel and sole, and means for adjusting the wedge heel gage and shoe gages relatively to each other and to the sole gage to adapt them for operating upon shoes of different shapes.

12. A pad box for use in applying pressure to shoe bottoms having, in combination, a pad for receiving a sole and shoe, a gage for locating an end portion of the sole in a predetermined position on the pad, a second gage for positioning the corresponding end portion of a shoe bottom member adapted to be interposed between the shoe bottom and the sole in the finished shoe, means for adjusting said second gage lengthwise and widthwise relatively to the sole gage, and means for adjusting said second gage and sole gage as a unit lengthwise of the pad.

13. A pad box for use in applying pressure to shoe bottoms having, in combination, a pad for receiving a sole and shoe, a gage for locating the heel end of the sole on the pad, a second gage for positioning the rear end of a wedge heel relatively to the sole, and means for permitting said wedge heel gage to yield heightwise of the pad box relatively to said sole gage.

14. A pad box for use in applying pressure to shoe bottoms having, in combination, a pad for receiving a sole and shoe, a gage for locating an end portion of the sole in a predetermined position on the pad, a second gage for positioning on the sole the corresponding end portion of an intermediate shoe bottom member adapted to be interposed between the shoe and sole in the finished shoe, a pair of gages arranged to engage the opposite edge faces of the sole adjacent to its shank portion, means carried by said pair of gages for positioning the adjacent portion of said shoe bottom member relatively to the sole, another pair of gages for positioning the end portion of the shoe relatively to the shoe bottom member and sole, and means for adjusting all of said gages as a unit lengthwise of the pad.

15. A pad box for use in applying pressure to shoe bottoms having, in combination, a pad for receiving a sole and shoe, a gage for locating an end portion of the sole on the pad, a second gage for positioning relatively to said sole the corresponding end portion of an intermediate shoe bottom member adapted to be interposed between the shoe bottom and sole in the finished shoe, a pair of equally and oppositely movable gages arranged to engage the shank portion of the sole and position said shoe bottom member relatively to said sole, and means for adjusting said pair of gages relatively to each other so that they will engage the sole substantially simultaneously.

16. A pad box for use in applying pressure to shoe bottoms having, in combination, a pad for receiving a sole and shoe, a forked gage for locating the heel end of the sole in a predetermined position on the pad, a second forked gage for positioning the rear end of a wedge heel relatively to the sole, means for adjusting said second gage lengthwise and widthwise relatively to said first gage, a pair of gages for engaging the opposite edge faces of the shank portion of the sole, means carried by said pair of gages for positioning adjacent portions of the wedge heel relatively to the shank portion of the sole, connections between the sole gages and wedge heel gages at each side of the sole for adjusting said gages relatively to each other, means for moving said pair of shank gages equally and oppositely toward and away from the sole, and means for

adjusting the opposite gages of said pair laterally with respect to each other so that they will engage the opposite edge faces of the sole substantially simultaneously.

17. A pad box for use in applying pressure to shoe bottoms having, in combination, a pad for receiving a sole and shoe, a forked gage for locating an end portion of a sole on the pad, means for positioning relatively to the sole the corresponding end portion of a shoe bottom member adapted to be interposed between the shoe and sole in the finished shoe, said means comprising a slide mounted in a guideway in the pad box for movement longitudinally of the sole and having a guideway in its forward end extending widthwise of the sole, a slide mounted for movement in said widthwise guideway and having a guideway in its forward side extending substantially heightwise of the sole, another slide mounted for movement in said heightwise guideway, means for yieldingly supporting said last-named slide in the heightwise guideway, means for adjusting the first-named slide longitudinally of the sole, means for adjusting the slide in the widthwise guideway laterally of the sole, and a gage secured to the slide in said heightwise guideway for engaging and positioning the end portion of said shoe bottom member.

18. A pad box for use in applying pressure to shoe bottoms having, in combination, a pad for receiving a sole and shoe, a gage for locating the heel end of the sole on the pad, a gage for positioning the rear end of a wedge heel relatively to the sole, a pair of gages arranged to engage the opposite edge faces of the sole at the shank portion thereof, means carried by said gages for positioning the forward portion of the wedge heel relatively to the sole, another pair of gages for positioning the heel portion of the shoe relatively to the wedge heel and sole, and means for adjusting the pair of shoe gages laterally relatively to the pair of sole and wedge heel gages.

19. A pad box for use in applying pressure to shoe bottoms having, in combination, a pad for receiving a sole and shoe, a gage for engaging the heel end of the sole and locating it in a predetermined position on the pad, another gage arranged to engage the rear end of a wedge heel and position it lengthwise relatively to the sole, and means for adjusting said gages relatively to each other in a direction lengthwise of the pad.

20. A pad box for use in applying pressure to shoe bottoms having, in combination, a pad for receiving a sole and shoe, a gage for engaging the heel end of the sole and locating it in a predetermined position on the pad, another gage arranged to engage the rear end of a wedge heel and position it lengthwise relatively to the sole, and means for adjusting said gages relatively to each other in a direction widthwise of the pad.

21. A pad box for use in applying pressure to shoe bottoms having, in combination, a pad for receiving a sole and shoe, a gage for locating the heel end of the sole on the pad, a second gage for positioning the rear end of a wedge heel relatively to the sole, the second gage being arranged for movement relatively to the sole gage in a direction heightwise of the pad box, and means for adjusting said gages relatively to each other.

22. A pad box for use in applying pressure to shoe bottoms having, in combination, a pad for receiving a sole and shoe, a gage for locating the sole on the pad, a carrier member for said gage, means mounted on said carrier member for positioning relatively to the sole a shoe bottom mem-

ber adapted to be interposed between the shoe and sole in the finished shoe, and additional means mounted on said carrier member for positioning the shoe relatively to said shoe bottom member and sole.

23. A pad box for use in applying pressure to shoe bottoms having, in combination, a pad for receiving a sole and shoe, a gage for locating the sole in a predetermined position on the pad, a carrier member for said gage, means carried by said carrier member arranged to position on the sole a shoe bottom member adapted to be interposed between the shoe and sole in the finished shoe, means additional to the last-named means for positioning the shoe relatively to said shoe bottom member and sole, and means for adjusting the gage and both positioning means relatively to one another.

24. A pad box for use in applying pressure to shoe bottoms having, in combination, a pad for receiving a sole and shoe, a gage for locating the sole lengthwise of the pad, a carrier member for said gage, means mounted on said carrier member for positioning on the sole a shoe bottom member adapted to be interposed between the shoe and sole in the finished shoe, and means for effecting relative adjustment heightwise of the pad between the last-named means and the sole locating gage.

25. A pad box for use in applying pressure to shoe bottoms having, in combination, a sole receiving pad, means for locating an end portion of a sole on the pad, means for positioning the corresponding end portion of a wedge heel on the sole, and means for effecting relative adjustment between said last-named means and the sole locating means heightwise of the pad.

26. A pad box for use in applying pressure to shoe bottoms having, in combination, a pad for receiving a sole and shoe, a gage for locating an end portion of the sole on the pad, means for positioning on the sole the corresponding end portion of a shoe bottom member adapted to be interposed between the shoe bottom and the sole in the finished shoe, means for adjusting said gage and said positioning means relatively to each other lengthwise of the pad, and means for effecting relative heightwise adjustment of said gage and said positioning means.

27. A pad box for use in applying pressure to shoe bottoms having, in combination, a pad for receiving a sole and shoe, a gage for locating the heel portion of a sole on the pad, a second gage for positioning a wedge heel relatively to the sole, and means for effecting relative adjustment of said gages heightwise of the pad.

28. A pad box for use in applying pressure to shoe bottoms having, in combination, a pad for receiving a sole and shoe, a gage for locating the sole on the pad, a carrier member for said gage, a second gage mounted on said carrier for positioning on the sole a shoe bottom member adapted to be interposed between the shoe bottom and the sole in the finished shoe, and means for adjusting said second gage heightwise relatively to the sole locating gage.

29. A pad box for use in applying pressure to shoe bottoms having, in combination, a pad for receiving a sole and shoe, a gage for locating the heel end of the sole on the pad, a second gage for positioning on the sole a wedge heel adapted to be interposed between the shoe bottom and the sole in the finished shoe, means for adjusting said gages relatively to each other lengthwise of the pad, and means for adjusting said second

gage heightwise relatively to the sole locating gage.

30. A pad box for use in applying pressure to shoe bottoms having, in combination, a pad for receiving a sole and shoe, a gage for locating an end portion of the sole on the pad, a second gage for positioning on the sole the corresponding end portion of a shoe bottom member adapted to be interposed between the shoe bottom and the sole in the finished shoe, means for adjusting said second gage heightwise relatively to the sole locating gage, and means for permitting said second gage to yield heightwise relatively to said sole locating gage.

31. A pad box for use in applying pressure to shoe bottoms having, in combination, a pad for receiving a sole and shoe, a gage for locating the sole on the pad, a carrier member for said gage, a second gage pivotally mounted on said carrier member and arranged to position on the sole a shoe bottom member adapted to be interposed between the shoe bottom and sole in the finished shoe, and means for adjusting said second gage about its pivot to vary its heightwise position relatively to the sole gage, said means also permitting said second gage to yield heightwise about its pivot relatively to said sole gage.

32. A pad box for use in applying pressure to shoe bottoms having, in combination, a pad for

receiving a sole and shoe, a gage for engaging the heel end of the sole and locating it on the pad, a second gage pivoted for swinging movement heightwise and lengthwise of the pad and arranged to position a wedge heel on the sole, means for adjusting said gages relatively to each other lengthwise of the pad, and means for permitting said second gage to yield about its pivot and swing heightwise and lengthwise of the pad relatively to the sole locating gage.

33. A pad box for use in applying pressure to shoe bottoms having, in combination, a pad for receiving a sole and shoe, a gage for locating the heel portion of the sole on the pad, a second gage for positioning a wedge heel on the heel portion of the sole, said gage being arranged to swing about an axis extending widthwise of the pad, means for adjusting said gages as a unit lengthwise of the pad, means for adjusting the sole locating gage lengthwise relatively to said second gage, and means for adjusting said second gage about its axis to vary its heightwise position relatively to the pad, said adjusting means being arranged to permit said second gage to yield and swing toward the pad under pressure but to return to its adjusted position when the pressure is relieved.

FRANCIS J. BETTER.
